SPINNING SPINDLE

Alejandro Handschin, Florida, Argentina

Application September 27, 1949, Serial No. 117,981

3 Claims. (Cl. 57—58)

1.

The present invention refers to an improvement in spinning spindles of the kind particularly designed to provide a double twist effect in the fibre bunches delivered by the front drawing train of continuous spinning machines.

Similar devices employed for like ends are already known to the art, but these known devices suffer from serious functional defects which greatly reduce their efficiency and which, in spite of numerous experiments made, have not as yet been overcome.

The spindle to which the present application refers is the result of constant trials made by experts in the art and considerable study applied to actual practice. It was thus possible entirely to eliminate the deficiencies of the devices known and used to date.

The constructive and functional features of the device object of the present invention offer, among others, the following advantages: Elimination of the traveller or slip ring and, consequently, of the spinning ring itself; this brings with it the considerable advantage of enabling the thread to be twisted, or of stepping up the rotation of the spindle which thus can turn at speeds far beyond what is common. For every simple turn of the spindle, likewise, the twist effect on the yarn is doubled, the output of yarn, at normal speed of the spindle, is therefore also twice that of conventional spindles operating at the same speed. As a result of increased rigidity and slower rotation of the bobbin, the yarn-carrying capacity of the latter is greater, without unbalancing the spindle, which considerably favours the output by diminishing the number of runs of the machine.

The apparatus similarly offers other important advantages, as will be made clear during the course of the present description.

In order that the present invention may be more clearly understood and readily put into practice, same will now be described with reference to attached drawings illustrating a preferred embodiment of its principles, said embodiment to be taken as an illustration and in no way as a limitation upon the invention.

In the drawings:

Figure 1 is a diagrammatic and partially sectional view of the spindle, showing the particular arrangement of its means and component parts, and

Figure 2 illustrates diagrammatically a constructive variation of a means coupling the spindle and the bobbin.

Like numerals represent like or similar parts throughout the several figures of the drawing.

2.

In the embodiment shown, the double-twist effect spinning spindle, improved according to the present invention, is mounted on a tubular base support 1, the vertical section of which is T-shaped. The cross limb 1' of same rests on the spindle-carrying frame 2 of the machine, bearing on a resilient washer or similar means 3. This support is suitably fixed to said frame by means of a nut 4 and washers 5.

10 The spindle itself consists of a cylindrical stem 6 the lower end portion of which is reduced in diameter and which is journaled in a set of ball bearings 7 constituting annular projections or shoulders provided within the tubular support 1. 15 A member 8 revolves on cylindrical member 1', said member 8 forming integral part of stem 6, its purpose being to cause the rotation of the spindle.

A further stem 9 projects vertically from said 20 member 8. It is provided with an axial bore-hole 10 which communicates with the outside through orifice 10' provided just above the driving member 8 and beneath a frusto-conical plate 11. The upper portion of this plate is provided with a flat 25 flange 12, edge 12' of which engages thread 13 coming from the drawing frame which, after passing through upper eyelet 14, is brought round in close contact with flange or edge 12' in order to pass through orifice 10' and axial bore-hole 10 of member 9, and passes through the open end 30 of said bore-hole and to bobbin 15.

On said stem 9, journaled on ball-bearings 16, a bobbin-carrier 17 is mounted, consisting of a sleeve the outside surface of which is cylindrically shaped and provided, close to its lower end, with an annular flange 17' serving to support said bobbin 15 when same is frictionally engaged over said surface. This bobbin-carrier 17 can rotate independently of or with the spindle, or can remain stationary when the same rotates. In the first case, the supporting means 16 permits free rotation, uninfluenced by stem or member 9; on the other hand, a friction means or clutch of any kind 18 will permit the bobbin carrier to be driven by the spindle, or remain stationary.

45 Outside said bobbin 15 a stationary cylindrical drum or shell 19 is arranged, mounted on bearings 30 that permit free movement of the spindle and its parts. This drum is equipped with means 50 for guiding the thread, which means consist of an upper eyelet 20 arranged adjacent to and below the plane defining the end of the bore-hole of stem 9, and of a small traveller or slip ring 21 which operates vertically in a guide slot 22 provided therefor in one of the generatrices of the 55 inside of said drum 19.

The slip or sliding action of said small ring or traveller 21 along its guide 22 is provided with an electro-magnet 23 operatively arranged outside of said drum 19 to reciprocate parallel to the axis of the bobbin substantially in front of said guide-slot. The proper tension of thread 13 is obtained by any suitable means, such as a soft-acting brake or similar arrangement 24.

The thread or bundle of thread supplied by said drawing frame passes through eyelet 14 and, in close contact with the edge 12' of plate 12, through orifice 10' and axial bore-hole 10, on to eyelet 20 and slip ring or traveller 21, from which the winding of bobbin 15 takes place. As at this moment the spindle and its related operating parts 15 and 17 is functioning, the thread or bundle of threads is rotatively drawn by the spindle through orifice 10', its friction against edge 12' bringing about a slow rotation of bobbin 15 and its supporting sleeve 17. This permits said thread to be properly wound on the bobbin and, due to the sliding action of travelling ring 21, vertically moved by the electro-magnet, the correct position of the thread in bobbin form being thus obtained. As apparent, drum or shell 19 is stationary.

The brake means 18 provided at the upper portion of the spindle can likewise cooperate in transmitting the rotatory movement to bobbin 15—in this case partially retained by the tensioning effect of the thread caused by member 24, thus bringing about a slow rotatory displacement as the thread is delivered for winding.

The rotatory connection between spindle and bobbin-carrier 11 can be established, furthermore, by any known means. One of the many ways of effecting this transmission has been diagrammatically illustrated in Figure 2. In this device, stem 9 of the spindle has been fixed to a flat washer 25. This washer is magnetic and its central opening coincides with the axial perforation 10 of the stem.

Parallel to said washer 25 a second washer 26, of a larger diameter, has been arranged, properly centred with regard to aforementioned perforation. This member 26 is controllably mounted on the free end of the bobbin-bearing sleeve 17' by means of screws 27 which enable a greater or lesser spacing to be obtained between washer 26 and magnetized washer 25.

As is evident, when washer 26 approaches magnet 25, the intensity of the magnetic flux transmitted will increase, and the force of the drive will therefore be greater. On the contrary, when both members separate, the flux will reduce and the drive will slow down, as transmitted by the spindle to the bobbin carrier. These rotative transmission means can, naturally, replace any other mechanical means employed for similar purposes. As an alternative, the tractive effort of bobbin 15 and its corresponding support can be derived, as already explained, from the friction existing between the rotatory portion of said spindle and the bobbin; or, by the friction between the thread or bundle of threads against the edge 12' of plate 11.

All these variations are possible due to the perfect centralization and mounting of the com-

ponent parts of the spindle and its cooperating members which, in their assembled form, provide the many advantages for which protection is sought after.

The invention as described and illustrated may be clearly understood and no further explanations will be required by those versed in the matter.

As the invention herein shown and specified has been described in the manner of a preferred embodiment which is to be considered as an illustrative example and in no ways as a limitation upon the invention, same may be subjected to changes in its construction and details, without thereby departing from its essential nature, as clearly defined in the following claims.

I claim:

1. Improvements in spinning spindles particularly designed to provide a double twisting effect of the thread material supplied by the front drawing frame of a continuous spinning machine and comprising a frame, a spindle journaled in the frame and having an axial hollow in one end portion opening through that end and a transverse orifice communicating with the inner end of the hollow, a pulley on the spindle for driving same, a bobbin-carrier journaled on the hollow spindle end, a bobbin frictionally engaged by the carrier, a stationary drum surrounding the carrier and bobbin, means fixed to the drum and tensioning the thread material, other means on the drum guiding the tensioned thread material after its passage through the orifice and hollow, reciprocatory third means guided on the drum and feeding the thread material to the bobbin, a fourth means reciprocating the third means on the drum, and a frustoconical plate fixed to the carrier and frictionally engaged by the thread material prior to passage of the same through the orifice and rotated by the thread material to rotate the carrier during rotation of the spindle.

2. The combination according to claim 1 and wherein the other means guiding the thread material is an eyelet affixed to the inner surface of the drum, and the third means is a sliding ring.

3. The combination according to claim 2 and wherein the sliding ring is guided in a groove on the drum parallel to the axis of the bobbin and the fourth means is an electromagnet movable parallel to the axis of the drum and serving to hold the drum stationary and causing said ring to slide in said groove.

ALEJANDRO HANDSCHIN.
